UNITED STATES PATENT OFFICE

93,760

DESIGN FOR A FURNITURE LEG OR THE LIKE

Richard T. Campbell, Grand Rapids, Mich., as-
signor to Stickley Brothers Company, Grand
Rapids, Mich., a corporation of Michigan

Application August 16, 1934, Serial No. 52,965

Term of patent 3½ years

To all whom it may concern:

Be it known that I, RICHARD T. CAMPBELL, a subject of the King of England, residing at 300 Briarwood Ave., S. E., in the city of Grand Rapids, county of Kent, and State of Michigan, have invented a new, original, and ornamental Design for a Furniture Leg or the like, of which the following is a specification, reference being had to the accompanying drawing, forming a part thereof, in which:

Figure 1 is an elevational view of the furniture leg, the distinguishing, essential and dominating feature or characteristic of the design shown in full lines being a series or plurality of spool-like

portions, each of said portions being graduated in cross-sectional diameter from one end thereof toward its other end and each adjacent portion being graduated in cross-sectional diameter relative to its adjoining portion, the upper portion of the leg shown in dotted lines indicating a non-essential feature of the design.

Figure 2 is a cross-sectional view of the furniture leg on line 2—2 of Figure 1.

I claim:

The ornamental design for a furniture leg or the like, as shown and described.

RICHARD T. CAMPBELL.
